G. F. MERGELL.
ELECTRICALLY OPERATED RAILWAY SIGNAL MEANS.
APPLICATION FILED NOV. 20, 1911.

Patented July 7, 1914.

UNITED STATES PATENT OFFICE.

GEORGE F. MERGELL, OF LOS ANGELES, CALIFORNIA.

ELECTRICALLY-OPERATED RAILWAY SIGNAL MEANS.

1,102,779.

Specification of Letters Patent.

Patented July 7, 1914.

Application filed November 20, 1911. Serial No. 661,401.

To all whom it may concern:

Be it known that I, GEORGE F. MERGELL, a citizen of the United States, residing at Los Angeles, in the county of Los Angeles 5 and State of California, have invented certain new and useful Improvements in Electrically-Operated Railway Signal Means.

My invention relates to railway signal means which are particularly well adapted 10 to be used at railway crossings or the like, and has particular reference to an electrically operated danger semaphore arm or paddle, which is adapted to be moved to a concealed position to exhibit a clear semaphore arm or paddle, and to an exposed 15 position to conceal the clear semaphore arm or paddle, which serves as a support for the former when in its exposed position.

An important object of the invention is 20 to provide means of the above mentioned character, which are simple in construction, compact, strong, cheap to manufacture and reliable in operation.

Other objects and advantages of the invention will be apparent during the course 25 of the following description.

In the accompanying drawings I have 30 illustrated one complete example of the physical embodiment of my invention constructed according to the best mode I have so far devised for the practical application 35 of the principles of the invention.

Figure 1 is a side elevation of a post and 40 semaphore arm or paddle embodying my invention, and Fig. 2 is an edge view of the same.

In the accompanying drawings wherein 45 is depicted a preferred embodiment of the invention, the number 29 designates a hollow post with which is rigidly connected a horizontal clear semaphore arm or paddle 30. This clear arm or paddle 30 is of course relatively stationary, and is preferably painted white.

The number 41 designates a vertically 50 swinging danger semaphore arm or paddle, preferably red in color, and which is an inverted U-shaped device to straddle the arm 30 for concealing the same from view and to be supported thereby. The danger paddle or arm has its inner end mounted within the hollow post 29 the same extending through a longitudinal opening or slot 42 as shown.

The number 43 designates a transverse 55 pivot or shaft attached to the side walls of

the post 29. The danger arm or paddle 41 is pivotally mounted upon this transverse shaft. Rotatably mounted upon the shaft 43 is a grooved pulley 44, rigidly connected with the arm or paddle 41 by any suitable means to move therewith. Passed about the pulley 41 and having proper frictional engagement therewith to move the same, is a cable or cord 45 as shown. One end of this 60 cable or cord is attached to a movable core 46 of a solenoid 47 as shown. The opposite end of the cable 45 has a loose connection with a lever 48 pivoted at 49 to a suitable support. The lever 48 is provided with a 65 transverse opening 49' to receive the end of the cable 45 in which a knot 50' is formed to provide an obstruction too large to pass through the opening 49' in the lever 48. The outer end of the lever 48 operates 70 within a guide bracket 51 and is limited thereby in its upward and downward movement.

The number 50 designates a weight, 75 mounted upon the free end of the lever 48, 80 outwardly of the guide bracket 51 as shown.

The operation of the apparatus is as follows: When the crossing or track is clear the solenoid 47 is energized and the core 46 is drawn downwardly. This moves the 85 right portion of the cable in Fig. 1 downwardly to swing the arm or paddle 41 through opening 42 into the hollow post 29 concealing the same and exhibiting the clear arm or paddle 30. Upon the movement of the cable 45 through the first part 90 of its travel, the left portion thereof does not move lever 48 upwardly, the initial movement serving to draw the lower end of the cable upwardly in the opening 49' 95 of the lever. But upon continued upward movement of the cable the knob or obstruction 50' will engage the lever to elevate the same. When the crossing or track is in the condition of danger the solenoid 47 is 100 deenergized, whereby the lever 48 is dropped to trip or start the danger paddle 41 upon its downward movement, and such movement is completed by force of gravity.

Having thus fully described my invention, what I claim as new and desire to secure by Letters Patent is:—

1. In electrically operated railway signal means, the combination with a hollow supporting post and a stationary signal arm, 110 of a hollow signal arm pivoted in the post and formed with a wheel portion, a pull

cord passed over said wheel, a solenoid having its core connected to one end of said cord for holding the movable arm in the hollow post, and a weighted lever attached 5 to the other end of the cord for moving the movable arm to obscure the stationary arm, when said solenoid is deenergized.

2. In electrically operated railway signal means, the combination with a supporting post of a stationary signal arm and a movable signal arm U-shaped in cross section and adapted to incase the stationary arm, electrical means adapted to hold said movable arm out of operative position, and 15 means for swinging the movable arm to position to obscure the stationary arm when the electrical means is deenergized.

3. In electrically operated railway signal means, the combination with a hollow supporting post of a stationary signal arm and a movable signal arm U-shaped in cross section and adapted to incase the stationary arm, mechanism for moving the movable arm to obscure the stationary arm, and electrical means to hold the movable arm out of 20 operative position, and said mechanism comprising a cord attached to the movable arm and to said electrical means. 25

In testimony whereof I affix my signature in the presence of two witnesses.

GEORGE F. MERGELL.

Witnesses:

R. COTTON,
FRED HOWLAND.
